UNITED STATES PATENT OFFICE.

HENRY H. DOERING, OF CHICAGO, ILLINOIS.

METHOD OF AND APPARATUS FOR CRYSTALLIZING OILS AND FATS.

1,426,555.

Specification of Letters Patent. Patented Aug. 22, 1922.

Application filed February 16, 1920. Serial No. 359,024.

To all whom it may concern:

Be it known that I, HENRY H. DOERING, a citizen of the United States, and resident of Chicago, in the county of Cook and State of Illinois, have invented a certain new and useful Method of and Apparatus for Crystallizing Oils and Fats, of which the following is a description, reference being had to the accompanying drawing, which forms a part of my specification.

My invention relates to a method of treating or crystallizing animal fats and vegetable oils which are more particularly employed in the manufacture of oleomargarine and various other butter substitutes; as well as to the treatment or cooling of lard; the invention also pertaining to an improved apparatus or means for carrying out the method; one object of the invention being to provide an apparatus whereby the treatment or cooling may be more quickly effected and better and finer crystals provided.

One purpose of my invention is to provide an apparatus adapted to carry out my improved method whereby the hot vegetable oils, animal fats, or hot lard, will be introduced into the reservoir or receptacle containing a cooling medium and subjected to or forced through the cooling medium or cold water by the action of and in conjunction with compressed air; with the result that the oils or fats are more uniformly broken up into minute particles through the action of the air and cooling medium; the apparatus causing the oils or fats to be forcibly injected preferably at the bottom of the tank of cooling medium, which usually consists of ice water. As a result of my improved method, the oils or fats are not only more quickly cooled but finer and better crystals are provided; while my improved apparatus tends to keep the particles of crystallized oils or fats as well as the cooling medium or water in constant circulation; and as a result of the injected air under pressure and the constant circulation of the cooling medium produced thereby the cooling water is maintained at a lower temperature than would otherwise be the case.

The objects and advantages of my invention will be readily comprehended from the following detailed description of the accompanying drawing of means for putting my improved method into practice.

Figure 1 is a top plan view of my im-

proved apparatus, with an intervening portion thereof shown broken away.

Figure 2 is a vertical, sectional view, taken at the left-hand end of the construction disclosed in Figure 1.

Figure 3 is a detail sectional view of portions of the oil or fat introducing and agitating medium introducing means.

In the particular exemplification of apparatus embodying my invention and adapted to carry out my improved method, it comprises a tank or receptacle 10 of suitable dimensions and made fluid-tight so as to hold a sufficient quantity of cooling medium, which usually consists of cold water, as well as the oils or fats which are being treated. The receptacle, as shown in the drawing, is usually made rectangular and open at its top; and is preferably constructed of wood so as not to have deleterious effect on the oils or fats.

The tank or receptacle 10, preferably at one end thereof, is provided with a suitable conduit or feed-pipe 11, which is preferably made funnel shape at its upper end to facilitate the introduction of the heated oils or fats. This conduit or pipe 11 preferably extends vertically to a point near the bottom of the receptacle 10, where it enters or is provided with a suitable coupling 12, shown somewhat in the nature of a T-connection into which the heated oils or fats will be conveyed. The heated oils or fats may be fed in any suitable manner into the open funnel shaped upper end of the conduit 11 and caused to flow downwardly into the coupling 12 in advance of the discharge thereof into the cooling medium or cold water with which the tank or receptacle is provided; the oils or fats being discharged through the open extended end 13 with which the coupling or connection 12 is preferably provided.

The rear or opposite end of coupling or connection 12 is provided with a closure member 14 through which a tube or conduit 15 is disposed preferably substantially at the longitudinal center line of the coupling or connection 12; the tube 15 extending to a point beyond the point where the conduit or pipe 11 discharges into the coupling 12. The outer end of tube or pipe 15, which is disposed through the closure member 14, has connection, by means of elbow 16 with a conduit 17 which leads to the top

of the tank or receptacle. The conduit 17 and connections constitute an air-line which is intended to lead to a suitable supply of compressed air; the line 17 being provided 5 at any convenient point with a valve as at 18 for controlling the flow of air through said line.

The oil or fat-feeding conduit or pipe 11 is shown preferably provided with an 10 outer shell or tube 19 of greater diameter than that of pipe 11 so as to leave an intervening air space within conduit 19; said conduit being open at its upper end and disposed above the top of the tank or receptacle 10, while the lower end thereof is 15 suitably connected with the coupling or connection 12 so as to provide a fluid-tight joint therewith. The closure member 14 is provided with a suitable number of apertures 20, preferably disposed concentrically about tube 15 whereby the water or cooling medium is permitted to flow in small streams or jets into the coupling or connection 12 from what may be termed the 20 closed or rear end thereof and caused to mingle with the oil or fat and compressed air discharging through the extended end 13.

The bottom of the tank or receptacle 10, 25 at a point slightly forward or in advance of the discharging end 13 of coupling 12, is shown provided with a ledge or baffle 21 having an upwardly inclining surface presented in the path of the forcibly discharged oils or fats and water coming from the outlet 13 of connection 12. This ledge or baffle 21 will induce the discharged mass to flow upwardly toward the top and opposite end of the tank or receptacle.

My invention contemplates and is intended for the treatment or crystallization 40 of vegetable oils or animal fats, as more especially used in the manufacture of oleomargarine and various other butter substitutes, as well as for the treatment and cooling of lard; and the steps of the method and the operation of the apparatus consist in feeding the hot oils, fats or lard, through the conduit 11 whereby it is conveyed to the coupling 12 at the bottom of 45 the tank or receptacle, which latter has previously been provided with a suitable quantity of cold water. Simultaneously with the feeding of the hot oils or fats into the conduit or pipe 11, valve 18 in air-line 17 is 50 operated so as to permit a sufficient quantity of compressed air to flow through pipe or conduit 17 and be discharged through tube 15 at a point preferably in advance of the 55 points where the hot oils or fats enter coupling 12. The action of the compressed air will induce the hot oils or fats, with the minute quantities of cold water entrained through apertures 20, to be forcibly discharged into the bottom of the tank of cold 60 water where it will encounter the upwardly 65

inclining baffle 21 which tends to force the small crystallized particles of oil or fats to move toward the opposite upper end of the receptacle or tank 10. The action of the compressed air discharging into coupling 12 will also cause the oil or fat to rapidly flow downwardly through conduit 11 and the compressed air will cause the oils or fats, together with the action of the water, to be broken up into small particles or globules and therefore greatly enhance the crystallization of these oils or fats. The discharging compressed air, as well as the entrained oils or fats and water, will provide a constant circulation of the water in the tank or receptacle which tends to maintain the water in cool condition; while at the same time a superior and finer crystal is provided than with the methods at present employed; and also a more rapid cooling of the crystals effected. By providing the feed-pipe or conduit 11 with a larger shell or sleeve 19, the inflowing hot oils or fats will not freeze or congeal within the feed-pipe or conduit 11, because of the air space provided about said feed pipe or conduit; at the same time a rapid flow of the oils or fats will also be induced through the suction action created by the discharge of compressed air into the coupler or discharge connection 12 rearward of the discharge orifice of said connection 12, thereby preventing any coagulation within the conduit or pipe 11 and therefore preventing any clogging up of the feed-pipe or conduit.

The tank or receptacle 10, at the end where the introducing conduits are located, is provided with a deflector or splash plate 22, which extends from the conduit 19 at a point intermediate of its ends, namely a point below the normal water level in the tank, in a diverging or flaring manner toward the top of the tank, where the deflector is suitably secured to the walls of the tank. The object of the deflector is to force the air and oil crystals to travel longitudinally of the tank toward the opposite end thereof.

A further object of the deflector or splash plate 22 is to prevent the air bubbles rising at a point immediately above the discharge end 13, from bursting upward through the cooling medium or water and thereby causing the water and oil crystals to be thrown or splashed out over the top of the tank and result in a loss of some of the oil crystals.

The rising air and oil bubbles will come into contact with the deflector and in seeking the top of the cooling water will be forced to travel toward the uppermost end of the deflector and therefore toward the opposite end of the tank. This action of the air and oil crystals will also assist in maintaining a constant circulation or movement

of the water, with the result that a more rapid cooling of the oil crystals is brought about.

The apparatus herein shown and described for carrying out my improved method I believe to be the simplest and best adaptation, but it may be modified in certain respects without, however, departing from the spirit of the invention and without affecting the 10 method herein presented.

What I claim is:—

1. An apparatus of the class described, comprising a water-holding receptacle, an oil or fat feed-pipe extending into and toward the bottom of the receptacle, means for admitting minute quantities of water at the discharge end of said feed-pipe, and a compressed air conduit communicating with the discharge end of said feed-pipe so as to cause 15 the small quantities of water to flow in contact with the oil and the commingled oil and water to be ejected with the air into the cooling water of said receptacle.

2. An apparatus of the class described, comprising a water-holding receptacle, a hot oil or fat feed-pipe extending into the receptacle and terminating near the bottom thereof in a laterally disposed discharge provided with small apertures in advance of the 20 discharge orifice of the pipe, and a compressed air conduit extending into said laterally disposed discharge of the oil or fat feed-pipe to a point in advance of the point of entry of the oil or fat into said discharge, 35 relative to the orifice thereof.

3. An apparatus of the class described, comprising a water-holding receptacle, a hot oil or fat feed-pipe extending into the receptacle and terminating near the bottom 40 thereof in a laterally disposed discharge, a compressed air conduit extending into said laterally disposed discharge to a point in advance of the point of entry of the oil or fat into said discharge, relative to the orifice 45 thereof, and deflecting means arranged in the receptacle in the path of the discharged crystals of oil or fat and air.

4. The method of crystallizing oils, fats and the like, which consists in introducing 50 a stream of hot oil or fat at the bottom of a body of cold water, and discharging a jet of compressed air adjacent the point of oil introduction so as to cause the oils or fats to be broken up into small particles or crystals.

5. An apparatus of the class described, comprising a tank or water-holding receptacle, an oil feed-pipe leading toward the bottom of the tank or receptacle and terminating in a laterally disposed discharge, 60 a compressed air-line extending into the tank and terminating in the laterally disposed discharge of said feed-pipe so that the oil will be forced into the water and broken into small particles and caused to crystallize, and 65 means whereby the oil or fat particles are

directed toward the surface of the water at a point removed from the point of introduction.

6. An apparatus of the class described, comprising a water-holding tank or receptacle, an oil or fat feed-pipe extending into the tank below the top thereof and terminating in a laterally disposed discharge, and a compressed air conduit communicating with said feed-pipe discharge in advance of the 75 oil discharge therein, relative to the discharge orifice, so as to cause the oil to be entrained therewith and to be forcibly ejected into the water.

7. An apparatus of the class described, comprising a water-holding receptacle, a hot oil or fat feed-pipe extending into the receptacle and terminating near the bottom thereof in a laterally disposed discharge, a compressed air conduit extending into said 85 laterally disposed discharge to a point in advance of the point of entry of the oil or fat into said discharge, relative to the discharge orifice thereof, a baffle member disposed in said receptacle in proximity to the 90 discharge orifice of said laterally disposed discharge, and deflecting means arranged adjacent to the top of the receptacle whereby the rising oil and air globules or crystals are deflected toward the opposite end 95 of the receptacle.

8. An apparatus of the class described, comprising a water-holding receptacle, a hot oil or fat feed-pipe extending into the receptacle and terminating near the bottom 100 in a laterally disposed discharge, said discharge being provided with a plurality of small apertures in advance of the discharge orifice, and a compressed air conduit extending into said laterally disposed discharge to a point in advance of said apertures and the point of entry of the oil or fat into said discharge, relative to the discharge orifice thereof, a baffle member disposed in said receptacle in proximity to the 105 discharge orifice of the laterally disposed discharge.

9. An apparatus of the class described, comprising a water-holding receptacle, a hot oil or fat feed-pipe extending into the 115 receptacle and terminating at its bottom in a laterally disposed discharge, said discharge being provided with a plurality of small apertures in advance of the discharge orifice thereof, a compressed air conduit extending into said laterally disposed discharge to a point in advance of said apertures and the point of entry of the oil or fat, relative to the discharge orifice thereof, an air jacket disposed about said feed-pipe intermediate of the upper end and the discharge thereof, and means arranged adjacent the top of the receptacle whereby the rising oil and air globules or crystals are deflected 120 toward the opposite end of the receptacle.

1. An apparatus of the class described, comprising a water-holding receptacle, a hot oil or fat feed-pipe extending into the receptacle at one end thereof and terminating at its bottom in a laterally disposed discharge, said discharge being provided with a plurality of small apertures at a point rearward of the point where the oil or fat enters said laterally disposed discharge, an
- 10 air jacket disposed about said feed-pipe intermediate of the upper end and the discharge end thereof, a compressed air conduit extending into said laterally disposed discharge to a point in advance of said
- 15 apertures and the point of entry of the oil or fat into said discharge, relative to the discharge orifice thereof, and deflecting means arranged adjacent the top of the receptacle and disposed from said feed-pipe toward the opposite end of the receptacle 20 whereby the rising oil and air globules or crystals are deflected toward the opposite end of the receptacle.
